CIRCULAR KNITTING MACHINE

Stanley R. Shelmire, Laconia, N. H., assignor to
 Scott & Williams, Incorporated, Laconia, N. H.,
 a corporation of Massachusetts

Application March 27, 1940, Serial No. 326,282

10 Claims. (CL 66—59)

This invention relates to independent needle circular knitting machines, and more particularly to such machines when adapted to make patterned fabric by manipulation of the knitting elements. One object of the present invention is to produce a machine of the cross-over type in which the entire manipulation is caused without the use of a second cam race. It is characteristic of the invention that the cross-over effect and knitting wave are obtained in a single cam race and that all the needles are drawn down to the knocking-over point at each feed. The invention is intended for use in a multi-feed machine and it can make either plain and tuck, or plain and float patterns. By the "cross-over" system is meant the type of "memory" system in which, for instance, certain needles make regular stitches at one feed while the others make the special form of stitch at that feed, and at a subsequent feed the situation is reversed without interposition of the pattern selecting mechanism. The cross-over can be caused after knitting one or a plurality of feeds. The invention will be shown embodied in a machine containing electro-mechanical selecting means of the type shown in the application of Albert E. Page Ser. No. 201,650, filed April 12, 1938, now Patent 2,225,842, for Circular knitting machine, and using the needle of the patent to Albert E. Page No. 2,129,148, dated September 6, 1938.

In pattern devices selecting individual knitting elements of the memory type, it has heretofore been necessary to use a cam race for the selected jacks or needles separate from the knitting cam race, or to interfere with the knitting movements of the needles. By means of the present invention the sliding butt needle of the Page Patent 2,129,148 can be employed as a memory device in a cross-over type of mechanism with the use of a single cam race for the knitting and the memory means. According to this invention all the needles pass through the regular knitting wave at each feed, and all the needles are brought down to the knocking-over point at each feed. Thus, with one cam setup, certain needles can be caused to float at one or more successive feeds while the others knit regular stitches, and thereafter for one or more feeds the needles which knit regular stitches can be caused to knit float stitches, while the ones which were making float stitches will now make regular stitches. All this is achieved in a single cam race by a simple cam system making use of the sliding butts of the needles. There is vertical separation of the

needles only when clearing or taking the yarns.

In the drawings:

Fig. 1 is a view in elevation, partly broken away, of part of the needle cylinder and pattern mechanism of a revolving needle cylinder circular knitting machine embodying the new invention;

Fig. 2 is a developed view in elevation of the sliding butt needles and a schematic single cam race layout of the machine of Fig. 1 with the needle butts being selected without the interpositioning of pattern jacks, adjusted to make float stitch and plain stitch; the needles moving from left to right and the vertical arrows indicating the knocking-over points of the two feeds shown;

Fig. 3 is a developed view in plan of the needles and cam race of Fig. 2;

Figs. 4 to 8 are views in vertical section through the needle cylinder of the machine shown in Figs. 2 and 3, the views being taken on the lines 4—4, 5—5, 6—6, 7—7 and 8—8 respectively, of Fig. 2, looking in the direction of the small arrows. Fig. 4 shows one needle at normal level just after its sliding butt has been depressed by the selecting hammer, and another needle whose butt was not depressed just after riding up the thin clearing cam at the first or left feed in Fig. 2; Fig. 5 shows a needle before and after being lowered by the knocking-over cam at the first feed; Fig. 6 shows needles raised to the dividing height from the knocking-over point at the first feed; Fig. 7 shows a needle with an extended butt returned to normal level by a thin dividing cam; Fig. 8 shows the extended butt needle of Fig. 7 traveling under the clearing cam at the second or right hand feed of Fig. 7, and also the depressed butt needle while being raised by the clearing cam and after it has been completely raised and its butt reset;

Fig. 9 is a perspective view of a sliding butt cylinder needle suitable for use in the new machine;

Fig. 10 is a view in elevation from the right side of Fig. 1, showing the selecting hammer and associated parts;

Fig. 11 is a plan view of the hammer acting directly on the needle butts of Figs. 2 to 4, inclusive;

Fig. 12 is a development similar to Fig. 2, of a modified form of cam race embodying the invention, adjusted to make tuck and plain stitches, the needle selection being caused directly on the needle butts by a trick or notched wheel;

Fig. 13 is a developed plan view similar to Fig. 3, of the needles and cams of Fig. 12;

Figs. 14 and 15 are views in vertical section through the modification of Fig. 12, the views being taken on the lines 14-14 and 15-15 respectively of Fig. 12; Fig. 14 showing three needles, one beginning to ascend the clearing cam at the first or left hand feed in Fig. 12, another with depressed butt riding on the tuck ledge of that cam, and a third at the top of the clearing cam; Fig. 15 showing a needle on top of the tucking cam at the second or right hand feed of Fig. 12;

Fig. 16 is a plan view, partly broken away, of the edge of the notched wheel of Fig. 12 engaging the needle butts, the arrows representing the directions of movement of the parts; while

Fig. 17 is a view in radial vertical section through the needle of the modification of Fig. 12, taken on the line 17-17, showing the notched trick wheel and its driving gear for engaging the needle butts.

In selecting needles for the forming of special stitches for pattern effects on independent needle circular knitting machines having a multiplicity of feeds, it is necessary, for reasons of economy of space and simplicity, to make one pattern selecting mechanism effective for a plurality of feeds by means of a memory device such as a cross-over system in which after producing a pattern selection at one or more feeds, the machine will automatically switch or cross over to another selection without the use of a second pattern mechanism. The present invention achieves this end in a very simple manner without the use of pattern jacks, thus freeing a machine containing pattern jacks to use those elements for other purposes.

The embodiments of the invention shown in Figs. 1 to 10 will be described first. In these embodiments the special stitch employed is a float stitch and the special stitches are made on the cylinder needles. This machine is a rib knitting machine with a revolving needle cylinder in which the dial needles n knit at each feed but the cylinder needles may be so managed as to knit only once for each revolution of the machine or only once for each of a plurality of feeds. In Fig. 2 each cylinder needle knits once in each two feeds. The machine has a bedplate B supporting a rotary needle cylinder 260 in which independent cylinder latch needles N move vertically in slots, as usual. The needle cylinder is surrounded by a stationary cam cylinder or ring 271.

One of the objects of this invention is to produce a machine which can knit large designs, that is to say, designs in which a large number of adjacent needles all knit the one pattern yarn. The other pattern yarns, of course, must be floated in back of these needles, and to prevent such floats, which would be objectionable the machine contains in addition the following elements. There is a dial D containing dial needles n and actuating cams (not shown) there being as many dial needles as there are cylinder needles. As a result, rib fabric is obtained. The dial needles knit at each feed, and since they take the floats which are formed by the cylinder needles, I get two courses of rib stitches for each course of cylinder stitches. The stitches knit by the dial needles appear on the inside of the fabric only and it is therefore immaterial if the two courses of rib stitches are of different colors—they do not affect the pattern on the outside of the fabric. The appearance of the inside of

the fabric is similar to that produced by an ordinary two-feed machine.

Carried above the needle cylinder 260 and the dial D my means of a bracket 34, ring 32 and posts 31, is a large pattern drum or cylinder 33 whose axis is coaxial with that of the needle cylinder. Around the lower edge of this pattern cylinder is a gear ring (not shown) which, through appropriate gearing, drives the pattern cylinder in synchronism with the needle cylinder. In the example shown in Fig. 1, the two cylinders revolve in a clockwise direction. On the surface of the pattern cylinder is pasted or otherwise represented the design which it is desired to 15 reproduce in the fabric. It is necessary that the representation of the design be colored in such manner and the rest of the machine arranged so that only the needles which are to take the pattern yarn at any given feed will be 20 selected, and all the other will not be selected. For example, electrical apparatus may be so arranged that when a ray of light from a lamp or light source is reflected from a reflecting substance on the pattern cylinder, onto the plate 25 of a photo-electric cell 36, current is transmitted through the wires 55 and the corresponding cylinder needle does not take the yarn at 5. The remainder of the pattern may be black which will not reflect enough light to cause the electrical apparatus to function and the cylinder needles corresponding to this part of the pattern cylinder will take yarn and knit at 5. We will assume that we are making float stitch patterns by the use of the setup in Fig. 2, and that a pattern such as shown opposite the scanner 36 in 30 Fig. 1 is to be produced. In this figure a shield shown with dotted portions 37 is superposed on a background indicated by cross-hatching 38. The dotted parts 37 are colored silver and the cross-hatched parts 38, black. The pattern (dotted) or silver portions will be produced by the cylinder needles which knit at the second or 35 right hand feed of Fig. 2, and the background (cross-hatched) or black portions will be produced by the yarn which is knit by the cylinder needles at the first or left hand feed.

The needles to be selected are constructed in accordance with the patent to Albert E. Page No. 2,129,148, above mentioned, and contain a 40 sliding operating butt. Butts of two different lengths can be presented to the knitting cams by the needle. The needle is shown in perspective in Fig. 9 and has a shank 22 and a fixed low operating butt 23 extending laterally from the shank, as usual. This butt projects laterally from the shank in the plane of the hook of the needle on the upper side of the shank, and is of considerable width in order that the novel 45 sliding butt 26 may project through it. The sliding butt moves in the plane of the hook and the fixed butt in a slot 27 cut in one side of the shank of the needle and the fixed butt. The sliding butt is held in the slot in a frictioned manner by means of a spring finger 28 riveted to the fixed butt and overlying the slot 27 opposite the low butt. The length of the sliding butt is such that it either projects beyond the back or lower edge of the shank of the needle or beyond the low or fixed butt. When it is projected beyond the low butt, it is adapted to cause one manipulation of the needle, and when it is depressed until it is flush with the fixed butt, the needle receives a different manipulation. It has been found possible to cause 50 all the necessary movements of the sliding butt

without rocking the needle or otherwise disturbing its longitudinal and knitting operations, though it might be noted that its longitudinal movement can be availed of to reset the sliding butt after the selection has been used. For this purpose there is a depression or groove 28 in the needle cylinder underneath the needle of such depth that when the sliding butt is pushed downward, i. e., inward till its upper end is flush with the top of the low fixed butt, the lower or rounded end of the sliding butt will not quite contact the bottom of the groove. The pushing upwardly, i. e., outwardly of the sliding butt is obtained automatically without reference to any selecting means, whenever the needle is pushed upward until the rounded end of the sliding butt contacts the bevelled upper end 30 of the groove 28 when it is cammed outwardly to its extended position (see Fig. 8). In the constructions of Figs. 1 to 10, certain needles must retain their knitting loops and pass below the knitting cams without taking yarn, i. e., welting or floating, and it is those needles whose sliding butts are thus selectively depressed which make the special stitch at the first feed. After one or more feeds the cross-over takes place and it is the needle whose sliding butt was not depressed which makes the special stitch.

The selecting of the sliding butt may be done by various mechanisms such as an electro-mechanical hammer or a pattern wheel, but in the constructions shown in Figs. 1 to 10, the selecting is done by electro-mechanical hammers and mechanisms which will now be described. These selecting mechanisms comprise essentially a pattern scanning device having rotary movement relative to the pattern, electric means operated by that scanning device which in turn may cause a single element to have mechanical movement directly on the sliding butts or other individual elements which are moving past this single element with the same angular speed as that at which the pattern is moving. The element which has mechanical movement directly on the individual elements to depress them can be the magnetically-operated hammer 50 of Figs. 2, 3 and 11, which has been found to move fast enough to select a single needle or a group of needles in accurate accordance with the pattern passing the scanning device and with sufficient force to drive the sliding butts inward until they are flush with the fixed low operating butts. The scanning device is an electric eye or photo-electric cell 36 moved vertically by a screw shaft 46. The revolutions of the shaft 46 are determined by the driving gear 80 on the bottom of the shaft, which driving gear is driven by a train of gears 88, 89, 90, from the main gear ring 73 for the needle cylinder.

In the mechanism shown in Figs. 1 and 10, a hammer 78 is used which does not act directly on the butts of the needles. Driven from the main gear ring is a horizontal wheel 70 carrying a plurality of small horizontal jacks 78 arranged in radial grooves on the wheel and held in position by a cap 71. The connection between the main gear ring 73 and the wheel 70 comprises a gear 74 meshing with the main gear ring, and a vertical spindle 72 carrying the gear 74 and the wheel 70. The drive for this horizontal wheel 70 and the spacing of the horizontal jacks 78 therein are such that as the needle cylinder revolves and the horizontal wheel turns, a horizontal jack comes opposite the sliding butt of each needle in the needle cylinder.

The horizontal jacks 78 rest on their lower edges, and these are curved so that the jacks can rock according to whether their inner or outer ends are pushed down. The end of the hammer or armature 78 overlies the outer ends of the horizontal jacks as they come around to a point radially outward from the needle cylinder, and this hammer 78, operating through a notch in the cover 71, can depress the outer ends of the jacks. The cap or cover 71 does not revolve. The hammer 78 is pivoted at 54 with tension spring 52 tending to keep the hammer in retracted position. There is an electromagnet 53 adjacent the end of the hammer opposite the operating end, this electromagnet being adapted to turn the hammer about its pivot point. There is a stationary cam plate 77 fastened on the lower side of the cover 71 which is adapted to act on the horizontal jacks to complete the selection started by the hammer 78. This cam plate also assists in repositioning the jacks for their next selection by the hammer. When the horizontal jacks are projected, the rotation of the horizontal wheel causes the jacks to move in through an opening 76 in the cam ring into engagement with the corresponding sliding butt and depresses same to the position shown in Figs. 1 and 4.

As mentioned above, it will be obvious that the electro-magnetic hammer could operate directly on the sliding butts rather than through the intermediary of the horizontal jacks 78, and this simplified arrangement is the one indicated diagrammatically in Figs. 2 and 3, and more specifically in Fig. 11. In this form of the invention the hammer 50 is pivotally carried on a frame 51 with a tension spring tending to keep the operating end of the hammer 50 in retracted position. There is an electromagnet adjacent the other bent end of the hammer opposite to the operating end, as in the construction of Fig. 10, this electromagnet being located in sufficient proximity to turn the hammer about its pivot point, and bring the operating end into engagement with a sliding butt whenever the electromagnet is energized (see Fig. 11).

The sliding butts can also be selected by means which are wholly mechanical, such for instance as the trick wheel construction shown in Figs. 16 and 17, and, incidentally, shown in Figs. 12 and 13. Referring to Figs. 16 and 17, the low fixed butts 23 as well as the sliding butt 26 project radially from the walls of the needle cylinder, and advantage is taken of this fact to use a trick wheel 79 mounted on a vertical axle 80 revolving at the level of the high butts. There are flat-ended teeth 84 on the periphery of this trick wheel, spaced in accordance with the pattern. Wherever there is such a tooth, revolution of the wheel will depress the corresponding sliding butt to a position flush with the low or fixed butt 23. Whenever such a tooth is cut off, the sliding butt 26 will remain in its uppermost position, i. e., projected beyond the fixed butt. For the purpose of turning this trick wheel in timed relation with the needles, there is a gear wheel 82 mounted just above the trick wheel on the same axle, having teeth 83 around its periphery which are slightly longer than those on the trick wheel. The teeth on the gear wheel are offset with relation to the trick wheel teeth so that they overlap and intermesh with the low or fixed butts 23 of the needles. As a result, the turning of the needle cylinder will cause the gear wheel and trick wheel to be turned in

timed relation with them. The teeth on the gear wheel will fall in the space between the needles, and the teeth on the trick wheel will be opposite the needles, as above described. The gear wheel and the trick wheel operate through a slot 85 in the cam ring 271. While all of the embodiments which we have described are with relation to the cylinder needles, it will be obvious that if it should happen to suit the patterning needs, the sliding butt needles and their selecting mechanisms and cams could be used in the dial of the machine.

The cam ring layout for taking advantage of the selectively distinguished positions of the butts of the needles to provide the peculiarly simple and elastic construction of this invention is shown in Figs. 2 and 3. In these two figures the needles are moving from left to right and two feeds are shown, the knocking-over points being indicated by the two vertical arrows. It might be stated at the outset that with the exception of cams 130 and 133, the cams are all of such a depth that they extend inwardly toward the needle cylinder far enough to engage the fixed low butts. The upper part of cam 130 at the left hand feed as viewed in Fig. 2 functions as a clearing cam but does not clear those needles which are to be left at the special stitch level. This special stitch level may be any level which does not clear the latch but produces a special stitch, e. g., tuck or float. The upper part of cam 130 is thin and while it extends inwardly from the cam ring 271 far enough to engage the extended sliding butts, it is spaced from the needle cylinder far enough to miss the fixed low butts of the needles. In the example shown in Fig. 2, the non-clearing needles at the left hand feed are being left at a welted level which will result in a float stitch, and the shoulder on cam 130 for holding the needles with depressed sliding butts therefore occurs at the elevation marked 136, which is the normal level of the needles.

The butts of the needles travel in a single or closed cam path, all the needles going through exactly the same movement except during the time when latches are being cleared and yarns taken in the hooks of the needles. Thus according to the present invention the knocking-over cam 131 at the left hand feed and the knocking-over cam 135 at the right hand feed engage all the needles and bring them down to the knocking-over level, and the selection as to the sliding butts occurs when the needles are all at one level. As already explained, the needles with projecting sliding butts, i. e., those whose sliding butts were not pushed radially inward by the hammer 50, will engage the thin portion of the cam 130 and ride up to the clearing point, after which they will take yarn, be drawn down by the knocking-over cam 131 and knock over their stitches. The needles whose sliding butts were depressed by the hammer 50 will ride along the ledge 136 at the welted or float level and will not take yarn but will be drawn down to the knocking-over level by the cam 131, all the needles then being raised together by their fixed butts engaging the raising cam 132. In Fig. 2 the projecting sliding butts are shown solid, and the depressed sliding butts in outline only. As the needles come to the end of the high portion of the raising cam 132, the actual cross-over is started by the low or thin cam 133. This is a lowering cam which precedes the clearing cam at the right-hand feed and it is adapted to push down below the lower end of the clearing cam 134 the butts

of all needles whose sliding butts project and therefore took yarn and knitted at the left hand feed. Such needles passing under the clearing cam 134 are engaged by the knocking-over cam 135 at the right hand feed and are drawn down to the knocking-over level along with the needles with depressed sliding butts, which in the meantime have passed the special thin lowering cam 133 without being affected by it, have been cleared by cam 134 and taken yarn.

It will be noted that the raising cam 132 serves to raise the low butt needles to a level where they will subsequently be engaged by the clearing cam 134. This clearing cam 134 raises the low butt needles to a higher level than the cam 130 raised the high butt needles at the left hand feed, because the low butt needles must be raised high enough to reset their sliding butts in the manner shown in Fig. 10 of the Page Patent 2,129,148. The high butt needles which rode up the cam 130 remain projected to the full extent throughout their passage through the cam path and therefore do not need to be raised to this level. It will be noted that the two cams which engage the high butt needles only, namely, the clearing cam 130 and the lowering cam 133, differ only in that the clearing cam 130 moves the high butt needles up so that they can knit at the left hand feed, and the lowering cam 133 moves them down so that they will not knit at the second feed. The sliding butt cross-over arrangement above described can be used to take care of the knitting at several different numbers of feeds. Thus while in the drawings I have shown the arrangement taking care of only two feeds, the cross-over need not occur at the second feed. On a four-feed machine, for example, the first two or three feeds could be provided with a cam like cam 130 and the cam 133 could be placed at the third and fourth, or at the fourth feed only. If a cam 133 were placed at both the third feed and the fourth feed, then it would be the low butt needles which would knit regular stitches at the third and fourth feeds. In this case the clearing cam 134 would be at the fourth feed and a clearing cam of the height of cam 130 would be used at the third feed. Repetition of the selection at the first feed would be obtained at the second feed by the use of another cam 130 and elimination of cams 133 and 134. It will also be obvious that, if desired, the thin cams 130 and 133 can be made radially movable out of operative relation with the high butt needles, so that regardless of pattern selection, all needles would knit regular stitches at the feeds where cams 133 were withdrawn and all needles would float or welt at the feeds where cams 130 were withdrawn. If it was desirable to knit on all needles at feeds where cams 130 were used, this cam might be moved in so that it would contact and raise the needles by their solid butts, and yet the selective patterning described would be resumed at any feed where such special or low cam was not retracted to miss high sliding butts or moved into contact and raise solid butts. It is also possible to introduce a reselection of the butts after a cross-over, as shown for instance by the cam 137 and the second selecting armature 50' shown at the right of Fig. 2. The cam 137 serves to lower the needles to the normal level where the sliding butts can be selected out by the next armature or hammer 50'. In this case the machine would have several feeds in addition to those shown in Fig. 2, and these other feeds would be located between the arma-

ture 58 and the armature 50, in the direction of movement of the needles as they appear in Fig. 2.

In Fig. 12 I have shown a cam layout in accordance with the present invention, adapted to make a somewhat different type of special stitch, i. e., a tuck stitch instead of a float stitch. In this form a selective tucking cam 138 is substituted for the clearing cam 134 of Fig. 2, and a tucking cam 138 is placed in a position below the clearing cam 134. With these two cams 138 and 138, tuck stitches instead of float stitches will occur at the needles which do not knit at that particular feed. The cam 138 has a normal thickness up to the tuck height, where there is a setback ledge 140 along which the needles will pass when their sliding butts have been depressed. At cam 138 those needles which rode all the way up cam 138 because their sliding butts were still projected, will be lowered to escape the clearing cam 134 and will then be elevated to tuck level by cam 138 so that they will take yarn at the second feed without casting their loops, thereby producing the open tuck of modern knitting, as distinguished from what is sometimes called a tight or closed tuck. It will be seen that by making the tucking cam 138 retractable or by splitting the cam 138 vertically so that the ledge portion is movable vertically from tuck to float level and back, it is possible to change one or the other of special stitches produced by this cross-over from tuck to float or vice versa. As in the case of Fig. 2, however, all needles are brought down at each feed to the knocking-over level, which is slightly below the normal level at which their butts are selected by the armatures, trick wheels or the like.

As an example of how this new invention can be employed, attention is called to the use of color. If yarns of different colors are used at the two feeds, as for example, one color at the left hand feed and another at the right hand feed (as in Fig. 2), a pattern of one color can be made at the left hand feed and a background of another color at the other feed. The yarn which floats or tucks at the cylinder needles will be taken in by the dial needles.

The construction of the machine having been described, its operation will be set forth in connection with Figs. 1 and 10 and the needle cams of Figs. 2 and 3. When the scanner 36 scans a cross-hatched or black portion of the cylinder, i. e., the background, which is to be knit by the cylinder needle at the left hand feed, no electric current is transmitted to the armature 78 and the horizontal jack 75 does not have its inner end tipped up into contact with the cam 77 which would cause projection of the jack. Thus the horizontal jack, not having been selected, will not be projected; the sliding butt of the needle will not be depressed and will ride all the way up cam 138 to the top, clearing the needle and insuring that it takes yarn at the left hand feed. When the scanner 36 scans a silver or dotted portion of the pattern, it transmits an electrical impulse to the armature 78, which depresses the outer end of the pattern jack, rocking the inner end upwardly into contact with its operating cams, as shown in the issued Page Patent 2,139,148, which will cause projection of this horizontal jack in time to depress the sliding butt of the corresponding needle. This needle then will not rise above the special stitch level 138 which is substantially at the normal level of the needles as shown in Fig. 2 and therefore in this particular example will not be

elevated at all. As a result the needle is not cleared and does not take yarn at this feed but is drawn down to the knocking-over level along with the other needles. The fixed operating butts of all the needles ride up the cam 132 and as they pass off that cam the needles with projected sliding butts, i. e., those which form the background by knitting at the left hand feed, are drawn down by the cam 133 and pass below the clearing cam 134. The needles with depressed sliding butts do not engage this thin cam 133 and ride up the clearing cam 134 and take yarn at this right hand feed. All the needles are drawn down to the knocking-over level by the cam 135 acting on the low butts. Thus at the right hand feed the cylinder needles which are knitting the pattern knit in their yarn, completing the patterning operation. The needles are raised to normal level, or slightly above it, and then lowered into accurate line for reselection by means of cam 137. If instead of the hammer acting on the pattern jacks the construction is used in which there are no pattern jacks, then the initial selection will be by hammer 58 and the reselection by hammer 50' of Fig. 2. If there are only two feeds in the machine, the cycle of operations will repeat itself as necessary, and if the machine is a four-feed one, the other two feeds may be interspersed in any order desired.

Many other modifications of this invention which do not depart from the scope thereof will occur to those skilled in the art.

What I claim is:

- 35 1. A knitting machine having a needle bed, a plurality of independent needles therein, said needles being provided with sliding butts so that butts of two different heights may be presented to the knitting cams, means to selectively move certain butts so that certain needles have high and others low butts, a plurality of feeds, and cams at said feeds to give the needles different manipulations according to whether they present high or low butts, so that at the first feed following a selection those needles having high butts function in one manner and those needles having low butts function in a different manner, and at the second feed following said selection the actions of the needles are reversed.
- 40 2. A knitting machine having a needle bed, a plurality of independent needles therein, said needles being provided with sliding butts so that butts of different heights may be presented to the knitting cams, means to selectively move certain butts so that certain needles have high and others low butts, a plurality of feeds, and cams at said feeds to give the needles different manipulations according to whether they present high or low butts, so that at the first feed following a selection those needles having butts of one height will knit while those needles having butts of the other height will not knit and at a feed following said selection those needles which knit at the first feed will not knit and those needles which did not knit at the first feed will knit.
- 45 3. A knitting machine having a needle bed, a plurality of independent needles therein having hooks, shanks and fixed operating butts, in combination with a butt inside said fixed butt on each of a plurality of needles adapted to slide with relation to the shank and to project beyond the fixed butt in the plane of the hook or to be buried therein, means to selectively move certain sliding butts to the level of the fixed butts,
- 50 4. A knitting machine having a needle bed, a plurality of feeds and a single cam path to give
- 55
- 60
- 65
- 70
- 75

the needles different manipulations according to whether they present a high or a low butt so that at the first feed following a selection, selected needles will function in one manner and unselected needles in a different manner and at the second feed following said selection the actions of the needles will be reversed.

4. In a multi-feed circular knitting machine, a series of independent needles, sliding operating butts on a plurality of said needles so that butts of different heights may be presented, and a knocking-over cam at each feed adapted to bring all the needles down to the knocking-over level, in combination with cam means adapted to cause needles presenting butts of one height to knit and to cause the needles with the other butt heights to fail to knit at the one feed and to reverse said functioning at another feed.

5. In a multi-feed circular knitting machine, a series of independent needles, a single cam path for said needles, operating butts on said needles which slide with relation to the shanks of the needles so that butts of different heights may be presented to the cams, said cam path comprising a knitting cam and a clearing cam at each feed; the clearing cam at one or more feeds being adapted to select the needles into two groups by moving upwardly to clear level the needles presenting butts of one height, and a cam at one or more other feeds adapted to select downwardly so that they pass below the next clearing cam those needles which were cleared on passage by the preceding upwardly-selecting clearing cam, thereby giving a cross-over effect.

6. A multi-feed circular knitting machine with independent needles, sliding operating butts on a plurality of said needles and a single closed cam path for engaging said operating butts comprising a cam at each feed adapted to knock over all needles, a thin cam at one feed adapted to divide the needles into two groups according to butt height by clearing one of said groups, in combination with a thin cam at another feed adapted to lower the needles raised by the first-mentioned thin cam, and a clearing cam at said second-mentioned feed adapted to clear the needles missed by the second thin cam and to miss the butts of the needles lowered by said second thin cam, whereby a cross-over effect is obtained in the knitting cam path.

7. A multi-feed circular knitting machine with independent needles, sliding operating butts on a plurality of said needles, selecting means adapted to move said butts to produce differentiated butt heights, and a knitting cam at each of a plurality of feeds adapted to draw all of said needles down to the knocking-over level, in com-

bination with other cams forming a single closed cam path for said needles and comprising raising and lowering cams adapted to cause needles with butts of one height to clear and knit at certain feeds while needles presenting another butt height do not knit, and to reverse the selection at other feeds.

8. A multi-feed circular knitting machine having independent needles therein, sliding operating butts on a plurality of said needles and a selecting element adapted to arrange said butts to present high and low butts at one feed, in combination with a set of knitting cams for said operating butts comprising a knitting cam at each feed adapted to lower all needles to the knocking-over point, a selective clearing cam leaving low butt needles at a special stitch level at that feed, and selective cam means for lowering high butt needles to the special stitch level at another feed and below the clearing cam at that feed.

9. In a multi-feed circular knitting machine, independent needles, a needle bed, sliding operating butts on a plurality of said needles, a selecting element adapted to arrange said butts to present high and low butts at one feed, said sliding butts being of sufficient size to project below the shank when its needle presents a low butt, and a set of knitting cams for said operating butts comprising a selective clearing cam leaving low butt needles at a special stitch level at said one feed, and selective cam means for lowering high butt needles to the special stitch level at another feed, in combination with a clearing cam at said second feed permitting the high butt needles to pass below it, and camming means associated with the needle bed adapted to cam back to high-butt position the sliding butts of needles rising on the clearing cam at the second feed.

10. A multi-feed circular knitting machine having a needle bed, a plurality of independent needles therein having hooks, shanks and fixed operating butts, in combination with a butt inside said fixed butt on each of a plurality of needles adapted to slide with relation to the shank and to project beyond the fixed butt in the plane of the hook or to be buried therein, means to selectively move certain sliding butts to the level of the fixed butts, a cam path for said needle butts comprising a cam adapted to contact the high butts to clear those needles at one feed, and a cam adapted to lower said high butts at another feed, in combination with cams to complete the knitting waves at both said feeds by contact with the fixed or low butts.

STANLEY R. SHELMIRE.
